OTTO M. BRATRUD, OF SEATTLE, WASHINGTON

CUTTING INSTRUMENT

Application filed September 9, 1929. Serial No. 391,355.

My invention relates to and has for a purpose the provision of a cutting instrument of simple, substantial and compact construction, by which cutting or scraping operations can be manually effected with a blade embodied in the instrument, and with the utmost ease and dispatch.

It is another purpose of my invention to provide a cutting instrument of the above described character embodying means by which extremities or corners of the blade at its cutting edge such as the heel or toe of the latter can be exposed from the casing of the instrument for cutting operations, to the exclusion of the remainder of the blade, all while providing the necessary firm and stable support for the cutting edge of the blade.

It is a further purpose of my invention to provide a cutting instrument wherein its casing and a cap therefor co-act to provide a pair of spaced abutments for confining against axial displacement, a rotary actuator for a blade carrying holder in the casing, so that the actuator will be rendered operative for the advancing of the blade from the casing and its retraction into the casing.

Another purpose of my invention is the provision of a cutting instrument wherein the cap thereof is detachably secured to the casing, and the actuating means for the blade carrying holder is so associated therewith, that upon removal of the cap, the holder, blade and actuating means can be withdrawn as a unit from the casing for sharpening or replacement of the blade.

I will describe only one form of cutting instrument embodying my invention and will then point out the novel features thereof in claims.

40 In the accompanying drawings,

Figure 1 is a view showing in side elevation one form of cutting instrument embodying my invention, with the cutting edge of the blade exposed from the casing of the instrument for use.

Figure 2 is a view similar to Figure 1 and illustrating only the toe and heel portions of the cutting blade exposed from the casing for use.

50 Figure 3 is a longitudinal sectional view of

the cutting instrument shown in the preceding views.

Figure 4 is an enlarged longitudinal sectional view taken on the line 4-4 of Figure 3 and looking in the direction of the arrows. 55

Figure 5 is an enlarged transverse sectional view taken on the line 5-5 of Figure 3 and looking in the direction of the arrows.

Figure 6 is a perspective view of the blade holder embodied in the cutting instrument, 60 and

Figure 7 is a fragmentary perspective view of the casing of the instrument.

Referring specifically to the drawings in which similar reference characters designate similar parts in each of the several views, my invention in its present embodiment comprises a flat elongated casing C of metal, having one end extending obliquely as indicated at 10 and reduced in thickness as indicated at 11 to slidably receive a cutting blade B between its side walls 12 and 13, and firmly support the blade for movement through a slot 14 in the oblique end of the casing. The cutting blade is carried by a holder H in the form of a rectangular block of metal 15 insertable with the blade into the other and open end of the casing, which is provided with a slot 16 extending longitudinally of the casing from its open end. The inner end of the slot 16 provides a shoulder or abutment 17 for a rotary actuator A which is received in the slot 16 and forms part of an actuating means for the holder. 75 80 85

In the present instance the actuator A is in the form of a milled nut 18 threadedly mounted on a threaded rod 19 fixed against rotation to the holder H in any suitable manner. A cup shaped cap 20 telescopically receives and closes the open end of the casing; and the open end edge of the cap provides a second abutment 21 spaced from the abutment 17. With the cap applied to the casing as shown in the drawings, the actuator A is interposed between and is in abutting relation to the abutments 17 and 21, so as to be confined by the abutments against axial displacement and thereby be rendered operable when rotated manually in one direction or the other, to advance the blade from the casing 90 95 100

or retract it into the latter through the medium of the threaded rod 19 being fed axially by the actuator.

The cap 20 is detachably secured to the casing so as to be rendered removable, by the provision of a bead 22 formed on the inner wall of the cap, which is adapted to snap into a correspondingly shaped groove 23 formed in the outer wall of the casing, yet is disengagable from the groove when sufficient pull is exerted upon the cap in a direction to remove it from the casing.

In the present instance the blade B is provided with two cutting edges 24 and 25 at opposed ends thereof; and the blade is connected to the holder H for movement therewith yet is rendered reversible end for end on the holder for the use of one cutting edge or the other, by means of a pin 26 fixed to the holder and entering an opening 27 formed in the blade intermediate its ends, the blade seating flatwise in a recess 28 formed in the holder by reducing its thickness from one end.

25. The cutting edges of the blade extend obliquely thereof at the same angle as the oblique end 10 of the casing so as to be disposed parallel to the latter; and for the purpose of permitting only the extremities or the toe and heel portions of a cutting edge of the blade to be exposed from the casing for cutting operations, to the exclusion of the intermediate portion of the cutting edge as shown in Figure 2, the corners of the casing at its oblique end 10 are recessed as indicated at 29. It will be clear that by the provision of the recesses 29, either the toe and heel portions or the entire length of a cutting edge of the blade can be projected from the casing as desired or the 40 blade retracted into the casing, all in response to rotation of the actuator A in one direction or the other.

With the cap removed from the casing, the holder H, with the blade, the rod 19, and 45 actuator A, can be withdrawn as a unit from the casing by grasping and exerting a pull upon the actuator, thus permitting the blade to be reversed end for end on the holder for use of the other cutting edge of the blade, 50 or the blade resharpened or replaced with another.

Although I have herein shown and described only one form of cutting instrument embodying my invention, it is to be understood that various changes and modifications may be made therein without departing from the spirit of the invention and the spirit and scope of the appended claims.

I claim:

60. 1. A cutting instrument comprising a casing having an opening, a holder movably mounted in the casing, a blade carried by the holder, means for actuating the holder to project the blade's cutting edge through the opening, the casing being recessed in such

manner that a portion of the blade's cutting edge can be projected through the opening, while other portions of the cutting edge are disposed parallel with the walls of the opening and are rigidly supported by the walls 70 in the casing.

2. A cutting instrument comprising a casing, a holder movably mounted in the casing, a blade carried by the holder and having a cutting edge provided with toe and heel portions, means for actuating the holder to expose the cutting edge of the blade from the casing for cutting, and means whereby the toe and heel portions of the blade's cutting edge can be exposed from the casing for cutting, while the intermediate portion of the cutting edge is disposed in the casing.

3. A cutting instrument comprising a casing open at an end thereof, a holder insertable through the open end of the casing into the latter, a blade carried by the holder the casing having a slot extending from its open end to provide an abutment at the inner end of the slot, a cap closing the open end of the holder and providing a second abutment spaced from the first abutment, a threaded rod fixed to the holder, a nut threaded on the rod and disposed in the slot of the casing between the abutments so as to be confined by the latter against axial displacement and thereby co-act with said rod in advancing the blade into the casing or retracting the blade from the casing according as the nut is rotated in one direction or the other, and means for detachably securing the cap to the casing to permit withdrawal of the holder, blade, rod and nut from the casing as a unit, through the open end of the latter, when the cap is removed.
